US00D632150S

(12) **United States Design Patent**
Ruan

(10) **Patent No.:** **US D632,150 S**
(45) **Date of Patent:** **** Feb. 8, 2011**

(54) **TIGHTENER WITH INTELLIGENT CONTROL**

(75) Inventor: **Buqin Ruan**, Zhugang Town (CN)

(73) Assignee: **Zhejiang Topsun Logistic Control Co., Ltd.**, Taizhou (CN)

(**) Term: **14 Years**

(21) Appl. No.: **29/342,540**

(22) Filed: **Aug. 26, 2009**

(30) **Foreign Application Priority Data**

Mar. 11, 2009 (CN) 2009 3 0006519

(51) **LOC (9) Cl.** **08-05**

(52) **U.S. Cl.** **D8/44**

(58) **Field of Classification Search** ..... D8/14, D8/44; D34/33; 24/68 CD, 68 R; 254/217-220, 254/223, 247, 248; 401/100, 103

See application file for complete search history.

(57) **CLAIM**

The ornamental design for the tightener with intelligent control, as shown and described.

DESCRIPTION

FIG. 1 is a perspective view of a tightener with intelligent control showing the new design;

FIG. 2 is another perspective view of the tightener with intelligent control;

FIG. 3 is another perspective view of the tightener with intelligent control;

FIG. 4 is another perspective view of the tightener with intelligent control;

FIG. 5 is another perspective view of the tightener with intelligent control;

FIG. 6 is another perspective view of the tightener with intelligent control;

FIG. 7 is a front view of the tightener with intelligent control;

FIG. 8 is a rear view of the tightener with intelligent control;

FIG. 9 is a top view of the tightener with intelligent control;

FIG. 10 is a bottom view of the tightener with intelligent control;

FIG. 11 is a left side view of the tightener with intelligent control; and,

FIG. 12 is a right side view of the tightener with intelligent control.
